UNITED STATES PATENT OFFICE.

OLIVER D. WARFIELD, OF SPRINGFIELD, MASSACHUSETTS.

BIT-STOCK.

SPECIFICATION forming part of Letters Patent No. 267,732, dated November 21, 1882.

Application filed June 10, 1882. (No model.)

To all whom it may concern:

Be it known that I, OLIVER D. WARFIELD, of Springfield, in the county of Hampden and State of Massachusetts, have invented a new and useful Improvement in Bit-Braces, of which the following is a description and specification.

The object of my invention is to provide a bit-brace into which a boring-bit may be easily and quickly adjusted, and by which it will be securely and firmly held during the operation of boring; and I accomplish this by the mechanism substantially as hereinafter described, and illustrated in the accompanying drawings, in which—

15 Figure I is a side view of a bit-brace made according to my invention. Fig. II is a longitudinal section of the same through the socket portion of the brace, showing the fastening mechanism of full size; and Fig. III is an end 20 view of the socket end of the brace.

In the drawings, 1 represents the rod or main part of the brace, the end of which may be somewhat enlarged, and in which is made the socket, as 2, which is made to approximately fit the shank of any ordinary boring-bit, and on one side of this socket are made two ears, as 3, between which is pivoted, at 4, a cam, as 5, and a hole is made through one side of the socket end of the brace, through which 25 projects a spring-detent, as 8, secured to the brace, as at 7, and the cam, as 5, is made to impinge against this spring-detent and force it into the socket when the cam is in the position shown in black lines; but when the cam 30 is in the position shown in dotted lines its pressure against the detent is removed. A threaded hole is made through the side of the socket opposite the detent, as 8, through which may be turned a thumb-screw, as 9, so that its 35 inner end may project into the socket 2.

When it is desired to use this brace the shank of the boring-bit is inserted into the socket, as 2, with the thumb-screw 9 turned out, and the cam, as 5, in the position shown in dotted

lines, and the thumb-screw is then turned in 45 until its inner end strikes against the shank of the bit, and the cam 5 is then forced down into the position shown in black lines, which movement of the cam forces the detent 8 inward, with its inner end firmly pressed against 50 the shank of the bit on the side opposite the thumb-screw 9, and the bit is thereby firmly held in place in the socket of the brace. To loosen the bit it is only necessary to move the cam, as 5, into the position shown in dotted 55 lines, and the bit is then easily removed from the socket.

It is evident that instead of a flat spring, as 6, with one end attached to the detent and the other secured to the brace, as at 7, the detent, 60 as 8, may be provided with a shoulder on its outer end, and its hole counterbored, with a spiral spring placed therein and pressing outward against the shoulder on the outer end of the detent, to hold the latter always outward, 65 except when forced inward by the cam, as shown in dotted lines in Fig. II.

By using the adjusting-screw, as 9, the slight differences in the size of different shanks of bits may be easily compensated for, so that 70 the same movement of the cam and detent will always be sufficient to secure the bit in the brace-socket.

Having thus described my invention, what I claim as new is—

In an improved bit-brace, the combination, with the brace, provided with a socket to receive the shank of the bit, of a cam pivoted to the socket end, a spring-detent between said cam and the socket, and adapted to be forced 80 inward into the socket by the cam, and an adjusting-screw adapted to be turned into said socket on the side thereof opposite said spring-detent, substantially as described.

OLIVER D. WARFIELD.
